UNITED STATES PATENT OFFICE

GEORGE FRANCIS HOGAN, OF CHICAGO, ILLINOIS

CARTON

Application filed December 18, 1931. Serial No. 581,937.

This invention relates to cartons and more particularly to containers adapted for use in shipping liquids in glass receptacles.

Liquids such as table waters, soft drinks and the like are usually shipped in containers of wood having a plurality of cells or compartments to receive the bottles. Such containers are heavy and, because they are expensive, must be collected and returned at considerable cost. They are not suitable for shipment of bottled liquids by parcel post. Containers of corrugated or fibre board for single bottles have been used heretofore but no satisfactory multiple container adapted to hold and to carry a plurality of bottles safely under the conditions of parcel post transportation has been available heretofore.

It is the object of the present invention to provide a simple, light and inexpensive container which will hold a plurality of bottles containing liquids firmly and securely and will insure the safe transportation thereof, affording at the same time sufficient capacity to absorb the liquid of one or more of the bottles should any be broken in transit without permitting disintegration of the container.

In carrying out the invention I provide a container preferably rectangular in form of any suitable light and strong material such as corrugated or fibre board. The receptacle is provided, conveniently, with flaps at the top and bottom which are adapted to be folded over each other, the outer flaps meeting at their edges so that the receptacle can be sealed by means of adhesive tape. Within and at the bottom of the receptacle I provide a layer of resilient material, preferably corrugated board, upon which the bottles rest, and longitudinal and transverse partitions forming cells for the bottles. At the sides and ends of the container layers of resilient material such as corrugated board are so disposed as to form the outer walls of the contiguous cells, forming effective cushions to limit the force of blows delivered on the sides and ends of the container. At the top I provide a sheet of resilient material such as corrugated board which is adapted to rest on the tops of the bottles in the cells be-

neath the folded flaps. Thus the bottles in the cells are completely surrounded by cushioning material in addition to the walls of the container. Preferably the dimensions of the container are such that when the bottles are placed in the cells the overlying sheet must be pressed downwardly before the flaps are closed. This forces the tops of the bottles slightly into the resilient surface of the overlying sheet and firmly anchors each bottle in its cell.

The invention will be better understood by reference to the accompanying drawing illustrating the preferred embodiment in which

Fig. 1 is a view in perspective with parts broken away showing the container with the bottles therein;

Fig. 2 is a plan section through the container;

Fig. 3 is a longitudinal section through the container;

Fig. 4 is a transverse section through the container; and

Fig. 5 is a detail in section illustrating the embedment of the bottle tops in the overlying sheet.

Referring to the drawing, 5 and 6 indicate respectively the sides and ends of the container which may be made of any suitable light and strong sheet material such as corrugated or fibre board. The sides and ends may be made of one piece with the ends joined at one corner of the container by any suitable fastening, for example, strong tape 7. The sides and ends are provided at the bottom with integral flaps 8 and 9 and likewise at the top with integral flaps 10 and 11, the flaps being formed by bending the material. The flaps 8 and 10 are adapted to overlie the flaps 9 and 11 when the container is closed and the contiguous edges of the flaps 8 and 10 can be secured by any suitable fastening such as strips of tape 12 and 13, thus sealing the container.

In the bottom of the container a sheet 13 of cushioning material such as corrugated board is disposed and similar sheets 14 and 15 are disposed at the sides and ends within the container. Longitudinal and transverse

partitions 16 and 17 of like material divide the container into a plurality of cells each adapted to receive a bottle 18. A sheet 19 of cushioning material is disposed over the tops of the bottles beneath the flaps 10 and 11. As indicated more clearly in Fig. 5, this sheet is pressed downwardly upon the tops of the bottles so that depressions are formed in which the tops are held by the overlying flaps when the container is closed. Preferably the dimensions of the container are such that the sheet 19 must be pressed downwardly before the flaps 10 and 11 are closed and sealed, thus insuring that the bottles are gripped firmly between the sheets 13 and 19 with the top of the bottles locked against lateral movement by the depressions in the sheet 19.

Containers for any number of bottles up to twenty-four or even more may be made in accordance with the invention as described. The bottles and the liquid contents can be shipped with assurance against breakage under all normal and many otherwise hazardous conditions. The bottles are cushioned on all sides and unless the container is subjected to impact or crushing forces of unusual severity there is no chance that any bottle will be broken. However, if one or more bottles should be broken the cushioning material at the sides and bottom and the partitions forming the cells will readily absorb the liquid before it has a chance to soak into and weaken the outer walls of the container. Containers made in accordance with the invention have been subjected to severe tests by blows much heavier than any to which

they would be subjected in normal use. In those instances when breakage of the bottles occurred the liquid did not escape through or materially weaken the outer walls. The tests demonstrated the thorough practicability and advantages of the container and resulted in a ruling of the United States Post Office Department permitting shipment of liquids therein by parcel post.

Various changes may be made in the details of construction and arrangement of the parts without departing from the invention or sacrificing any of the advantages thereof.

I claim:

A shipping container for receptacles containing liquids comprising sides and ends formed from a single sheet of light strong material with integral flaps forming when closed the bottom and top of the container, sheets of cushioning material at the bottom and sides within the container, partitions forming cells within the container and a sheet of cushioning material loosely disposed above the partitions and beneath the flaps forming the closure at the top of the container, the latter sheet having a thickness greater than the distance between the top of the partitions and the inside top of the container, whereby said sheet has to be forced down upon the tops of the bottles as the top flaps are folded into closed position, thereby forming indentations in the sheet into which the tops of the bottles are received and securely anchored and means for sealing the flaps.

In testimony whereof I affix my signature.

GEORGE FRANCIS HOGAN.
